UNITED STATES PATENT OFFICE.

JULES C. LEVI, OF PATERSON, NEW JERSEY.

PEPPER-GRINDER.

SPECIFICATION forming part of Letters Patent No. 430,661, dated June 24, 1890.

Application filed March 21, 1890. Serial No. 344,746. (No model.)

To all whom it may concern.

Be it known that I, JULES C. LEVI, a resident of Paterson, Passaic county, and State of New Jersey, have invented an Improved Pepper-Grinder, of which the following is a specification, reference being had to the accompanying drawings, forming part of same, where-in—

Figure 1 represents a vertical central section of my improved pepper-grinder. Fig. 2 is a top view, partly broken away, of the lower part thereof; and Fig. 3 is a detail vertical section of the lower end of the rotary grinding-shell.

This invention relates to a new pepper-grinder for table use—that is to say, to a vessel which is to contain kernels of pepper, which, on turning the shell of the mill will be ground to the desired extent; and the invention consists in the details of improvement hereinafter more fully specified and claimed.

My improved mill consists of the following main portions, to wit: a base A, a grinding-shell B, a cap C, and a fastening-nut D. The base A has a tubular outer portion *a*, a perforated lower diaphragm *b*, from the center of which projects the stationary grinding-cone *d*, and a central stem *e*, which extends upward from the center of the stationary cone *d*. The outer circumference of the cone *d* is serrated or roughened to constitute a grinding-surface. The diaphragm *b* is perforated around the cone *d* to allow the ground particles to drop from the mill. The grinding-shell B is a hollow truncated cone, whose contracted lower portion contains on its inner side grinding ribs or projections *f*. The shell B is adapted to be inserted into the tubular outer portion of the base A, as in Fig. 1, so that the grinding-surfaces of *d* and *f* come close together sufficient for the purpose of reducing the kernels of pepper to the desired extent. The cap C is adapted to lap over the upper part of the cone *b* and to fit around the stationary stem or shaft *e*. Lugs *g* on the cap bear against lugs *h* on the shell B, so that

when the cap C is grasped and turned around the stem *e* it will carry the shell B around with it. The nut D is screwed upon the threaded upper end of the stem *e*, and confines all the parts in their desired relative positions, as in Fig. 1.

To fill the mill, the nut D is unscrewed, the cap C taken off, and kernels of pepper thrown into the shell B, whereupon the parts C and D are replaced. Whenever it is desired to have a certain amount of ground pepper, the person desiring to use it takes the mill in his hand—that is to say, takes hold of the base A with one hand and of the cap C with the other, and turns the cap C as long as desired. By turning the cap C he also turns the grinding-shell B and reduces the lower series of kernels, which lie between the grinding-surfaces *d* and *f*, to a powder, which escapes through the apertures *b*.

My improved grinding-mill, it will be seen, is of simple construction, can be conveniently cleaned, and is practically self-adjusting.

Having now described my invention, what I claim is—

1. In a grinding-mill, the combination of the base A, having perforated diaphragm *b* and stationary grinding-cone *d*, and central stem *e* with the grinding-shell B, having grinding-surfaces *f*, adapted to co-operate with the grinding-cone *d* and with the upper cap C, lugs *g* *h*, and nut D, substantially as herein shown and described.

2. In a grinding-mill, the combination of the base A, having perforated diaphragm *b*, and stationary grinding-cone *d*, with the grinding-shell B, having grinding-surfaces *f*, adapted to co-operate with the grinding-cone *d* and with the upper cap C, and means, substantially as described, for connecting it with the shell B, substantially as herein shown and described.

JULES C. LEVI.
